DESIGN FOR A HOUSING FOR SIGNAL DEVICE

Kenneth M. Lord, Canandaigua, N. Y., assignor
to The A. E. Rittenhouse Co., Inc., Honeoye
Falls, N. Y., a corporation of New York

Application December 1, 1939, Serial No. 88,609

Term of patent 14 years

To all whom it may concern:

Be it known that I, Kenneth M. Lord, a citizen of the United States of America, residing at Canandaigua, in the county of Ontario and State of New York, have invented a new, original, and ornamental Design for a Housing for Signal Device, of which the following is a specification, reference being had to the accompanying drawing, forming a part thereof.

In the drawing:

Fig. 1 is a front elevation of a housing for signal device showing my new design;

Fig. 2 is a side elevation of the same, and

Fig. 3 is a plan view of the same.

I claim:

The ornamental design for a housing for signal device, as shown.

KENNETH M. LORD.
